UNITED STATES PATENT OFFICE.

W. T. FRY, OF PHILADELPHIA, PENNSYLVANIA.

IMPROVEMENT IN FLASKS AND BOTTLES.

Specification forming part of Letters Patent No. 40,338 dated October 20, 1863.

To all whom it may concern:

Be it known that I, WILLIAM T. FRY, of Philadelphia, Pennsylvania, have invented an Improvement in the Necks of Bottles and Caps for the Same; and I do hereby declare the following to be a full, clear, and exact description of the same, reference being had to the accompanying drawings, and to the letters of reference marked thereon.

My invention relates to an improvement in that class of bottles or flasks to the necks of which are cemented screw-caps of metal for the reception of screw-stoppers containing cork or other elastic material for closing the mouth of the bottle, my improvement, which is fully described hereinafter, being such as to prevent the contents of the bottle from gaining access to and acting injuriously on the cement by which the screw-cap is secured to the neck.

In order to enable others to make and apply my invention, I will now proceed to describe the manner of constructing the same.

On reference to the accompanying drawings, which form a part of this specification, Figure 1 is a vertical section of part of a flask illustrating my improved neck and cap; Fig. 2, a plan view of Fig. 1, and Fig. 3 represents a section of the ordinary stopper or mouth for flasks.

In order that my invention may be readily understood, I will, in the first instance, proceed to describe the usual manner of forming the neck of an ordinary bottle or flask and cap for the reception of a screw-stopper, as illustrated in Fig. 3, where A' represents the neck of a flask, B' a portion of the leather covering, and C' the metal cap for receiving the screw-stopper E'. This cap consists of a metal ferrule with screw-threads on the outside, and on the top a flange, a', the ferrule, as well as its flange, being cemented to the neck of the flask. A stopper, E', is screwed onto the cap C', the internal elastic material, D', bearing on the top of the flange a', so that the cement at x must be constantly exposed to the contents of the flask.

Now, it is well known to those familiar with the manufacture and sale of this class of bot-

gles or flasks that there is great difficulty in maintaining the cap C tight on the neck, owing to the action of the contents of the bottle on the cement. The difficulty of obtaining a proper cement, capable of resisting the fluid contained in the bottle, is also well known. Thus a cement which would resist the action of water would not resist that of alcohol, and one that would resist the action of alcohol would not resist that of essential oils. In order to obviate this difficulty, I construct the mouth of the vessel in the manner seen in Fig. 1, the metal cap C being cemented to the neck of the vessel, as usual; but the flange a of the cap, instead of being cemented to the top of the flask, is cemented to a shoulder, y, formed on the neck, while the latter is reduced in diameter and continued upward, as seen at b. Above the flange a of the cap, and against this continuation of the neck, bears the cork or other elastic material, D, which is secured to the inside of the stopper E, the latter being screwed onto the cap C.

It will be evident that this simple improvement effectually prevents the contents of the flask from gaining access to and loosening the cement, by means of which the cap is secured to the neck of the vessel.

It will also be evident that the improvement is applicable to portable flasks for containing liquors, to inkstands, vessels for the toilet-table, druggists' bottles, &c., and that both cap and stopper may be made of vulcanized rubber or other hard material.

I claim as my invention and desire to secure by Letters Patent—

The neck A of the bottle and the cap C, both being constructed, adapted, and cemented to each other, and arranged for the reception of the screw-cap E, all substantially as set forth.

In testimony whereof I have signed my name to this specification in the presence of two subscribing witnesses.

WM. THO. FRY.
